UNITED STATES PATENT OFFICE.

RUDOLPH TIMROTH, OF CHICAGO, ILLINOIS, ASSIGNOR TO RAND, McNALLY & CO., OF SAME PLACE.

ADJUSTABLE FLY-TABLE FOR PRINTING-PRESSES.

SPECIFICATION forming part of Letters Patent No. 399,220, dated March 5, 1889.

Application filed July 23, 1888. Serial No. 280,703. (No model.)

To all whom it may concern:

Be it known that I, RUDOLPH TIMROTH, of Chicago, in the county of Cook and State of Illinois, have invented a new, useful, and Improved Portable and Adjustable Fly-Table for Printing-Presses, of which the following is a full, clear, and exact description, reference being had to the accompanying drawings, forming a part of this specification, in

10 which—

Figure 1 is a side view of a portion of a printing-press and a front view of my improved table in operative proximity thereto. Fig. 2 is a vertical longitudinal sectional view 15 of said table upon the line $x-x$, Fig. 1; and Fig. 3 is a sectional view of the same in plan, taken upon the line $y-y$, Fig. 2.

Like letters of reference in the different figures indicate like parts.

20 The object of my invention is to provide means whereby the top of a pile of sheets as they are delivered by the "fly" from a printing-press may be made to maintain substantially the same level as that of the axis of the fly, so that as the sheets accumulate and the pile increases it will not have to be removed from time to time, but may be permitted to remain until a large quantity is obtained, when the whole may be removed with the 25 30 table or support, thereby saving unnecessary handling and preventing the breakage and injury of the paper resulting therefrom.

To this end my invention consists in the combination of elements hereinafter more 35 particularly described, and definitely pointed out in the claims.

In my improved portable table I employ an ordinary platform hand-truck, in the drawings of which A represents the platform, which 40 is supported by suitable frame-work upon wheels a . Extending along the respective sides and across the ends, upon the top of said platform, are bars a' a'' , which are rigidly secured thereto. Pivoted to the bars a' 45 a'' , at or near the points b b , are bars B B, which are pivoted at their middle, b' , to the middle of like bars, C C, in the form of "lazy-tongs." The bars C C are pivoted at c, Fig. 2, to cleats d , rigidly secured to a table, D, 50 Figs. 1 and 2, the opposite end of which is

loosely supported upon friction-rollers b^2 , Fig. 2, upon the free ends of the bars B. Metal plates d' , Fig. 2, are provided to serve as bearings therefor. The lower ends of the bars C C are arranged to rest and slide upon plates a^3 a^4 , Figs. 2 and 3, upon the platform A, and are loosely attached to a cross-bar, E, through the middle of which is passed a horizontal screw, F, which is mounted in bearings f , rigidly attached to the platform A, the journal-bearings being smaller than the body of the screw, so as to prevent an endwise movement of said screw within the bearings. Upon the outer end of the screw F is attached a hand-wheel, f' , by which the screw may be 65 manipulated. The turning of the screw in one or another direction serves to raise or lower the table.

The operation of said device is as follows: The table is first placed so that its side is adjacent to and parallel with the end of a printing-press, G. The hand-wheel f' is then turned until the table D is raised substantially to a level with the axis of the fly g. The paper h is then delivered upon the table 75 in the usual way. As soon as it begins to accumulate above the desired level the hand-wheel is turned and the table lowered until it reaches its lowest level, as indicated in dotted lines in Fig. 2. The truck, with the table and paper thereon, is then drawn away and unloaded, when the operation may be repeated.

The advantage of said device is that fewer trucks are required to do a given amount of 85 work, and a great saving of space is accomplished, while the paper is not injured, as it is when so frequently handled under the old method.

Having thus described my invention, I 90 claim—

1. An adjustable portable fly-table for printing-presses, consisting of a hand-truck, a lazy-tongs mounted and pivoted thereon, a screw for actuating said lazy-tongs, and a 95 table mounted upon the latter, whereby the table may be lowered in proportion as the paper is placed thereon by the fly, substantially as shown and described.

2. The combination, with a printing-press, 100

of a table mounted upon lazy-tongs, a truck
for supporting said lazy-tongs, and a screw
and hand-wheel for actuating the same, whereby
the top of the paper pile may be made to
conform to the position of the fly, substantially
as shown and described.

In testimony whereof I have signed this

specification, in the presence of two subscribing
witnesses, this 14th day of June, 1888.

RUDOLPH TIMROTH.
